CLOSURE APPLYING MACHINE

**Dominic W. Tiano, Boston, Mass., assignor to
Pneumatic Scale Corporation, Limited, Quincy,
Mass., a corporation of Massachusetts**

Application July 18, 1936, Serial No. 91,395

9 Claims. (Cl. 226—88)

This invention relates to a closure applying machine.

The invention has for an object to provide a novel and improved construction of closure applying machine which is adapted to apply closures to containers in a manner such that the closures may be incompletely applied to the containers so that in such condition the containers may be readily evacuated, or partially so, without the complete removal of the closure.

A further and more specific object of the invention is to provide a novel and improved machine for applying screw closures to containers, and in which the containers are delivered from the machine with the closures partially screwed thereon so that in their unsealed condition the containers may be subjected to evacuation or to the introduction of gas therein through the space between the threads on the closure and container.

With these objects in view, and such others as may appear, the invention consists in the closure applying machine and in the various structures, arrangements, and combinations of parts hereinafter described and particularly defined in the claims at the end of this specification.

In the drawings illustrating the preferred embodiment of the invention, Fig. 1 is a vertical sectional view of the container supporting and closure applying mechanism; Fig. 2 is a sectional plan view of the driving section of the machine; Fig. 3 is a plan view of the closure applying mechanism shown in Fig. 1; Fig. 4 is a sectional plan view on the line 4—4 of Fig. 1, illustrating the chuck reversing mechanism; Fig. 5 is a vertical section of one of the closure applying mechanisms; Figs. 6 and 7 are sectional views on the lines 6—6 and 7—7, respectively, of Fig. 5; Fig. 8 is a detail partly in section of a portion of the closure applying chuck shown in Fig. 5; Fig. 9 is an inverted plan view of the closure holding member as seen from the line 9—9 of Fig. 5; Fig. 10 is a development of the cam for lowering and elevating the closure applying unit, and Figs. 11 and 12 are sectional side elevation and sectional plan views respectively of a modification to be referred to.

In general, in its preferred form, the present invention contemplates a machine for applying screw closures to containers such as bottles or jars, and in which provision is made for reversing the rotation of the closure applying unit to the end that the closure is unscrewed a predetermined amount so that the closure will rest loosely on the threads of the container leaving an

air space between the closure and the container, and in this condition the container may be conveyed from the machine to be subjected to a vacuum process with the closure in its incompletely applied condition. The present invention finds particular use in the packing of coffee or other materials in jars in which it is the practice to evacuate or partially evacuate the filled container before finally sealing the same. In the improved closure applying machine it is preferred to first completely screw the closure upon the container and to then rotate the closure in the reverse direction through a predetermined amount to partially unscrew the same and thereby obtain a uniform positioning of the closure on the container.

Referring now to the drawings, and particularly to Figs. 1, 2 and 4, the illustrated machine is provided with a base 2 having mounted thereon a closure feeding mechanism generally indicated at 10 and a revolute head 12 upon which are mounted to revolve therewith a plurality of and, as herein shown, four individual closure applying devices 14. Each closure applying device is arranged to be individually rotated during the revolution of the head to screw a closure 100 upon the threaded neck of a container 20 held by clamping members 16, 17 of a revolute container supporting table 18. The table 18 is arranged to revolve with the closure applying devices, and provision is made for engaging and releasing the containers at different stations in the revolution of the container supporting table.

The revolution of the revolute head 12 and also the container supporting table 18, is effected by a driving motor 24 arranged to drive a shaft 30 through pulleys 25, 26 and belt 28 as shown in Fig. 2. The driving shaft 30 is journaled in bearings 32 in a casing 34 secured to and supported by the base of the machine, and is provided with a worm 36 which cooperates with a worm wheel 38 formed on the lower portion of a cylindrical drum 40, see Fig. 1. A sleeve 42 is attached at its lower end to the inside of the cylindrical drum by the bolts 43, and at its upper end to the circular container supporting table 18 by a key 44. The clamping jaws 16, 17 above referred to for clamping the containers are mounted upon the revolute table to rotate therewith.

Provision is made for effecting the revolution of the closure applying devices 14 about a central supporting shaft 50 through connections between the closure applying devices and the sleeve 42, including, as shown in Fig. 1 an inner sleeve 55

46 having an elongated keyway 47 within which an elongated key 48 secured to the outer sleeve is slidably fitted whereby to effect rotation of the inner sleeve while permitting the vertical adjustment of the sleeve for the purpose of adjusting the vertical position of the closure applying devices to accommodate the machine to different heights of containers.

The closure applying devices are mounted upon the top of the inner sleeve 46 by a supporting bracket 52 held by a key 53 to the upper end of the sleeve. The bracket 52 has attached to it a plate 54 which forms a supporting member for the individual capping head casings 60 and to which they are fastened at their lower ends by screws 56. The individual capping head casings 60 are secured at their upper ends to the revoluble head 12 by screws 63 so that the rotations of the inner sleeve 46 are transmitted directly to the capping head casings and head 12 to cause the casings 60 to revolve about the stationary shaft 50, as will be apparent from an inspection of Fig. 1.

Each closure applying chuck indicated generally at 66 is mounted to slide vertically within the capping head casing 60 and a vertical motion is imparted to the individual chucks from a cam path 68 in a cylindrical drum 70, the upper end of which is secured to a flange 72 of a sleeve 74 keyed to the stationary shaft 50, as illustrated in Fig. 1. Each capping chuck is provided with a cam roller 76 which rides in the cam path 68, and, as illustrated in Fig. 5, each cam roller 76 is rotatably mounted on a stud 80 secured in an annular split collar 82. The halves of the split collar 82 are held together by means of screws 84 in an annular groove 86 cut in a chuck housing 88. An anti-friction bearing 90 on the stud 80 guides the latter in a vertical slot 92.

Referring now to Fig. 1, the cap feeding mechanism 10 in the illustrated machine may comprise any suitable or known form of cap feeding mechanism, and as herein shown includes a hopper 101 for storing a bulk supply of the caps 100 and from which successive caps are selected and delivered right side up through a feed chute 105, and the operating mechanism for selecting and delivering successive caps into the feed chute 105 may comprise that illustrated in the U. S. patent to R. N. Doble No. 1,801,721, to which reference may be made for a complete description thereof.

During the application of the caps, the containers are supported on the table 18 and are firmly gripped and held from rotation by the clamping members 16 and 17. The clamping members are arranged to engage and release the containers at the different stations in the revolution of the table 18 and as herein shown each set of clamping members comprises the stationary jaw 16 and the movable jaw 17. The stationary jaw is secured directly to the table and the movable jaw is fastened to a vertical stud 130 which is pivotally mounted in the table 18. The movable jaw is arranged to be moved by an inner cam surface 132 through a roller 134 on a lever 136 pivoted on a pin 138 secured to the under side of the table 18. A second arm 140 of the lever 136 is connected to a lever 142 secured to the lower end of the vertical stud 130 by a connecting rod 144. The roller 134 is held against the cam 132 by a spring 146 which is connected at its other end to a stud extending from the underside of the table. In operation, as the table 18 revolves, the cam roller 134 acting on the cam 132 causes the

movable gripping jaw 17 to close and yieldingly hold the container in position to permit the closure applying operation to be performed during one portion of the revolution of the table and to release the containers so that they may be discharged during another portion of the revolution of the table.

Provision is made in the illustrated machine for transferring the caps 100 from the cap feeding mechanism 10 to the cap applying devices 66 while the latter are revolving, and as herein shown, see Figs. 1 and 3, each closure applying device is provided with an oscillatory transferring arm 150 mounted to revolve about the central shaft 50 with the closure applying devices as the latter revolve. Provision is made for effecting the oscillations of the closure transferring arms at such a point in the revolution of the closure applying devices about the shaft 50 as to enable the successive caps or closures to be withdrawn from the end of the closure feeding chute 105 and to be transferred to a position under the chuck 66 to be engaged by the latter during the revolution of the closure applying devices. As herein shown, each transferring arm is secured to a vertical shaft 152 and each shaft is arranged to be oscillated by a cam 154 through cooperating cam rollers 156 carried by a cam lever 158 secured to the shafts 152. Springs 160 hold the rolls against the cam. As herein shown, each transferring arm is provided with a hub 162 and during the operations of the machine the hub 162 is caused to pass under the endmost cap in the manner illustrated in Fig. 1 to deposit the cap 100 upon the hub 162.

Referring now to Figs. 1 and 4, during the revolution of the cap applying chuck 66 about the shaft 50, each cap applying chuck is caused to rotate about its own axis in order to completely screw the caps or closures upon the containers, and thereafter, as herein shown, the direction of rotation of the cap applying chuck is reversed to partially unscrew the cap a predetermined amount. As herein illustrated, each cap applying chuck is provided with a pinion 94 keyed to the top of the chuck housing 88 and each pinion 94 meshes with a stationary gear segment 96 secured to the sleeve 74, during that part of the revolution of the machine in which the cap is being applied. Also in mesh with each pinion 94 are idler gears 98 which are loosely mounted on studs 102 secured to the revoluble head 12. After the chucks 66 have been revolved in one direction a predetermined amount, the pinion 94 leaves the gear segment 96 and rotation of the chuck is momentarily interrupted until the idler gear 98 comes in contact with a smaller gear segment 104, which, through the idler 98, reverses the rotation of the cap applying chuck 66, as shown in Fig. 4. The gear segment 104 is secured to a flanged hub 106 which is keyed to the sleeve 74. In order to relieve the shock of the gears coming into engagement, the segments are yieldingly mounted and, as herein shown, the segment 104 is pivotally mounted on a stud 108. The outer end of the segment is provided with a bolt 110 which slides freely through a slot in a lug 112 extending from the flanged hub 106. A coiled spring 114 encircles the bolt between the segment 104 and the lug 112. A washer 115 and nut 116 provided on the bolt on the further side of the lug hold the segment 104 in normal engaging position with the idler gears 98. Similarly, the gear segment 96 is provided with a separate section 118 pivoted on a stud 120 secured

in the segment 96. The outer end of the section 118 is provided with a bolt 122 which extends through a slot in a lug 124 formed integral with the segment 96. A coiled spring 126 encircles the bolt between the section 118 and the lug 124 and yieldingly urges the segment outwardly while the latter is held in normal, engaging position by a nut 125 and washer 127 on the bolt on the further side of the lug. By reference to Figs. 1 5 and 10 it will be seen that the gear segments 96, 104 are positioned at different levels and that the idler gears 98 rotate with the pinions 94 without producing any effect until the idlers come in contact with the segment 104 whereupon the rotation of the pinion 94 is reversed. The pinion 94 is made of sufficient length to permit the segment 104 and idlers 98 to remain in mesh with the pinion 94 in the various vertical positions into which the pinion and chuck housing are moved 10 during the operation of the machine.

Referring now to Figs. 5, 7, 8 and 9, each closure applying device comprises a housing 88 slidably and rotatably mounted in the casing 60. The housing 88 is provided at its lower end with 15 the cap gripping mechanism 66 which is arranged to receive the cap. The gripping mechanism 66 comprises serrated jaws 170 radially mounted in a disc 172 secured to the lower end of a spindle 178. The jaws are urged outwardly 20 or into open position by springs 174 and, as herein shown, are closed by clutch fingers 176 which are pivotally mounted in the spindle 178. The second arms 180 of the clutch fingers bear against a conical surface 182 of a rod 184 which is arranged 25 to be raised and lowered during the operation of the machine, to open and close the jaws 170. As herein illustrated the rod 184 is yieldably mounted within the spindle 178, a spring 186 normally urging the rod upwardly 30 against a compressing member 188 which in turn is held in its adjusted position with relation to the spindle 178 by a cap 190 which is attached to the upper section of the spindle. The compressing member 188 bears against a rod 192 which 35 is provided at its upper end with a roller 194 cooperating with a stationary cam 196. The rod 192 is guided vertically in a turret 198 formed in the revoluble head 12. The cam 196 is secured to a flange 200 which is keyed to the stationary shaft 50. As the capping heads revolve 40 about the shaft 50, the cam 196 operates to press down the member 188, compressing the spring 186 and thus lowering the conical surface 182 permitting the jaws 170 to open.

The spindle 178 is rotated with the housing 88 through connections which permit slippage when the cap has been screwed down to the limit of the threads and provision is made to positively engage the driving connections when the 45 rotation of the housing 88 is reversed to unscrew the cap. As herein shown, a flanged sleeve 202, screwed onto the spindle, 178 is provided with pins 204 which engage in slots 206 with a driven member 208 of a clutch. A collar 210 provided 50 with pins 212 which are arranged to project into elongated slots 214 in the housing 88 forms the driving member of the clutch. A compression spring 216 supported between a flange 218 and a collar 220 urges the members of the clutch into 55 engagement. Referring now to Fig. 8, the driven member 208 of the clutch is provided with but two teeth, on opposite sides, one of which 222 is visible in Fig. 8. These teeth engage the teeth 224 in the driving member 210 and as herein shown are yieldingly urged together by the com-

pression spring 216 so that when the driving member is rotated in a clockwise direction the clutch members will rotate together until the cap has been screwed onto the container, whereupon the driven member comes to rest while the driving member is permitted to slip over the teeth 222 of the driven member. The clutch continues to slip until rotation of the housing in a clockwise direction ceases or until the pinion 94 leaves the gear segment 96 when the rotation is interrupted until the idler gear 98 engages the small gear segment 104 to cause the pinion 94 to rotate in a counter-clockwise direction. This rotation is transmitted to the driving member 210 of the clutch through the connections described and as herein shown, see Fig. 8, the teeth of the clutch members are designed for positive engagement in a counter-clockwise direction so that no slipping of the clutch can occur. In this manner, each cap is successively unscrewed uniformly to the end that a definite amount of air space is maintained between the closure and the container preparatory to evacuating the container. During the operation of the machine when the top of a container comes in contact with a cap held in the jaws of a chuck, provision is made for permitting the gripping mechanism to move vertically in the chuck housing 88 so that this portion of the chuck will have a universal floating centralizing action to more readily apply the cap to the container, particularly where there is any irregularity either in the cap or in the container, which would otherwise tend to throw the center of the cap out of line with the center of the neck of the container. This is accomplished by providing a conical surface 226 on the spindle 178 normally supported by a corresponding conical surface 228 on a collar 230 secured to the bottom of the chuck housing 88.

In the illustrated machine the containers are carried into the machine on a conveyor 232 of any suitable construction, such as parallel chains running over sprockets, not shown, and as the containers are received by the machine, provision is made for delivering the containers to the clamping jaws 16, 17 as the latter are moved into a receiving position. As herein shown, see Fig. 4, the containers are delivered onto a rotating disc 234 and thence conveyed by a toothed rotary member 236 to a position to be delivered onto the revoluble table 18 and to be received by the clamping jaws 16, 17 which have previously been opened ready to receive a container. The jaws close about the container and as described the container is moved through successive stations where the closure is first screwed onto the container and then partially unscrewed whereupon the jaws 16, 17 are opened and the container is guided to a rotary disc 238 which conveys the containers to a discharge conveyor 240. The latter may comprise a belt or any other usual or preferred form of conveyor for continuously removing the containers from the machine. Provision is made for driving both rotary discs 234, 238 and the toothed member 236 from a gear 242 cut upon the drum 40 and, as shown in Fig. 2, the gear 242 is arranged to mesh with a similar gear 244 secured to a vertical shaft 246 upon which the toothed member 236 is mounted. The gear 244 is arranged to mesh with a gear 248 upon a vertical shaft 250 upon which the rotary disc 234 is mounted. The rotary disc 238 mounted upon a vertical shaft 252 is arranged to be driven from the gear 244 through an idler 75

gear 254 and a gear 256 secured to the vertical shaft 252.

In the operation of the embodiment of the invention thus far described, the containers are guided between the rails 231, 233, onto the rotary disc 234 and then carried by the toothed member 236 to a position to be received by the clamping members 16, 17. During the rotation of the revoluble head 12, the transferring arm 150 has picked up a cap from the cap feed chute 105, and, at a point designated at A, see Figs. 4 and 10, the chuck 66 is opened and lowered to receive the cap. The chuck is then closed around the cap and raised to remove the cap from the transferring arm. As the machine continues in operation, with the cap and container in vertical alignment, the chuck 66 is rotated through the segment 96 and pinion 94, and, at a point designated B, the chuck is lowered to apply the cap 20 to the container. When the cap has been screwed all the way down, the clutch members 208, 210, are arranged to slip until the pinion 94 leaves the segment 96 when the rotation of the chuck is interrupted until, at a point designated C, the idler 98 in mesh with the pinion 94, engages the segment 104 which reverses the rotation of the chuck and through positive engagement of the clutch members 208, 210, unscrews the cap approximately $\frac{1}{4}$ of a turn, whereupon the chuck 30 releases the cap and the container with the cap loosely placed thereon is ejected from the machine, between guides 235 and 237 onto the rotary disc 238 which carries the containers to the discharge conveyor 240. As will be seen from an inspection of Fig. 10 the cam 68 is designed to raise and lower the chucks to cooperate with the cap feeding and applying mechanisms as above described. That portion of the cam between A and B is designed to first raise the chuck slightly 40 to permit removal of the transferring arm 150 and thereafter lower the chuck to apply the cap to the container. Rotation of the chuck is initiated at an intermediate point between A and B, see Fig. 4, so that the cap is being rotated 45 when it comes in contact with the container at B. The chuck continues to follow the low portion of the cam 68 during the cap applying and reversing operations, between B and C, whereupon the cam 68 raises the chuck to its high point to 50 permit the container to be ejected and to permit the transferring arm with a new cap to be moved into alignment with the chuck. A slight drop in the cam path 68 permits the chuck to pick up the cap whereupon a new cycle is started.

55 Referring now to Figs. 11 and 12, as herein shown, a modified form of the present invention is illustrated. In this modification the central shaft 51 is arranged to rotate and the operating cams 71, 197, and segmental gears 97, 99, attached 60 to the shaft 51 are arranged to rotate with it. The idler gear 99 is supported in a stationary bracket 301 attached to the machine frame, and likewise the single chuck casing 61 is secured to the underside of the stationary bracket. Thus 65 the chuck is raised and lowered, rotated and reversed in a manner similar to the embodiment illustrated in Figs. 1 to 10, except that the casing 61 is stationary and the shaft 51 is rotated. In operation the containers may be delivered to the 70 machine on a suitable conveyor 300 and then brought to rest on a platform 302 where a suitable clamping mechanism 304, 306, of any usual or preferred form may be employed to align the container with the chuck 67. The caps may be supplied to the chuck manually or through the 75

mechanisms shown and described in the United States patent to R. N. Doble, No. 1,801,721, above referred to.

From the above description it will be observed that the present closure applying machine is capable of successful operation upon varying types and sizes of closures and containers, and that by means of the positive unscrewing of the closure from its completely applied position, uniform operation may be obtained with the varying sizes and styles of closures.

While the illustrated embodiments of the invention have been described, it will be understood that the invention may be embodied in other forms within the scope of the following claims.

Having thus described the invention what is claimed is:—

1. In a closure applying machine, in combination, a rotatable closure applying device, container engaging means, means for relatively moving the container and said closure applying device toward and from each other, means for rotating the closure applying device to first screw a closure completely upon the container, and means for thereafter rotating the closure applying device in the reverse direction to partially unscrew the closure thus applied.

2. In a closure applying machine, in combination, a rotatable closure applying device, container engaging means, means for relatively moving the container and said closure applying device toward and from each other, means for rotating the closure applying device to first screw a closure completely upon the container, and means for rotating the closure applying device a predetermined amount and in the reverse direction to partially unscrew the closure thus applied.

3. In a closure applying machine, in combination, a rotatable closure applying device, container engaging means, means for relatively moving the closure applying device and container engaging means toward and from one another, means for relatively rotating the closure applying device and the container in one direction, and means for relatively rotating the closure applying device and the container in a reverse direction to partially unscrew a closure after the same has been completely screwed onto the container by rotation of the closure applying device in the first mentioned direction.

4. In a closure applying machine, in combination, a closure applying device having means for engaging a cap during the rotation thereof to screw the same onto a threaded container, means for rotating the closure applying device in one direction to apply the closure to the container, and means for thereafter effecting the relative rotation of the container and closure thus applied to partially unscrew the closure.

5. In a closure applying machine, in combination, a revoluble closure applying device, means for effecting the rotation of the closure applying device about its own axis during its revoluble movement, whereby to screw a cap entirely on a threaded container, said means including a segment adapted to remain in operative connection to the closure applying device during a portion only of its revolution, means for thereafter reversing the rotation of the closure applying device during a portion of the remaining part of its revolution, and revoluble container holding means for operatively supporting the container during the closure applying operation.

6. In a closure applying machine, in combination, a closure applying device adapted to en-

gage a cap to screw the same onto a threaded container, means for rotating the closure applying device including a clutch adapted to slip when the cap has been completely screwed onto the container, and means for thereafter positively rotating the cap and closure applying device in the reverse direction to partially unscrew the closure a predetermined amount.

7. In a closure applying machine, in combination, a rotatable closure applying device adapted to screw a closure onto the threaded container, means for rotating the closure applying device in one direction including a clutch adapted to slip when the closure has been completely applied to the container, a pinion connected to the closure applying device through said clutch, and means cooperating with the pinion for positively effecting rotation of the closure applying device in the reverse direction, said clutch having provision whereby slipping thereof is prevented during such reverse rotation.

8. In a closure applying machine, in combination, a closure applying device for engaging a cap to screw the same onto a threaded container, means for rotating the closure applying device

in one direction including a clutch adapted to slip when the closure has been completely screwed onto the container, a pinion connected to the closure applying device through said clutch, and a rotary gear adapted to engage said pinion to effect said rotation and to be thereafter disengaged from said pinion, and a second gear member adapted to engage the pinion after the first gear has become disengaged for effecting rotation of the closure applying device in the reverse direction to partially unscrew the closure, said clutch being constructed to slip in one direction only.

9. In a closure applying machine, in combination, a plurality of rotatable closure applying devices, means for rotating said devices in one direction including a pinion connected to each device, and a single gear adapted to cooperate with all of the pinions and to be disengaged therefrom after each closure has been completely screwed onto the container, and means for thereafter positively rotating each closure applying device in the reverse direction to partially unscrew the closure.

DOMINIC W. TIANO. 25
